UNITED STATES PATENT OFFICE

REYNOLD G. NELSON, OF CANTON, OHIO, ASSIGNOR OF ONE-HALF TO THE SPUN STEEL CORPORATION, OF CANTON, OHIO, A CORPORATION OF OHIO

SPUN-METAL MANUFACTURE

Application filed November 5, 1926. Serial No. 146,365.

My invention relates to spinning as from tubes, cups, and the like, of sheet or strip metal, articles of manufacture having internally threaded portions which may be integral with externally grooved portions having internal longitudinally extending ridges spun therein, such as filler tubes for automobile radiators and the like.

Many automobiles are provided with radiators having filler tube inlets provided with internal threads at their ends for receiving an externally threaded radiator filler tube cap, and for appearance and strength the filler tubes may be externally grooved below the internally threaded ends.

In producing such radiator filler tubes having internally threaded ends, it has been necessary to cut with dies or other cutting tools, the internal threads in the ends thereof, and such internal thread cutting operations have been relatively expensive.

The principal object of the present improvements is to provide apparatus and methods for spinning internal threads upon the inside of tubular articles such as radiator filler tubes; and a further object of the improvements is to provide an apparatus and method for spinning an internally threaded and externally grooved radiator tube during a single continuous rotation of the improved spinning arbor of the improved apparatus.

These and ancillary objects are attained in the present improvements by a construction and arrangement which may be described in general terms as including in combination with a spinning apparatus which preferably may be of the type set forth in my application for U. S. Letters Patent for metal spinning apparatus, Serial No. 134,432, filed September 9, 1926, an improved internal thread spinning arbor, improved double rotary spinning rolls, improved double trimming tools, improved means for inserting blank cups and the like on the arbor; and improved filler tube stripping means.

A preferred embodiment of the apparatus of the invention is illustrated in the accompanying drawings forming part hereof, in which:—

50 Figure 1 is a fragmentary plan view, with

portions in section of the improved metal spinning apparatus, the operations for spinning a filler tube as aforesaid having just been completed and the apparatus being in readiness for the next trimming operation;

Fig. 2, a fragmentary front elevation of the same, portions being illustrated in section, and the tool holder and trimming mechanism being removed, and the apparatus being illustrated as just having had a blank cup inserted upon the improved internal thread spinning arbor by means of the tailstock provided with the improved cup inserting sleeve;

Fig. 3, a fragmentary view similar to Fig. 2, illustrating the operation of the improved filler tube stripping mechanism of the apparatus;

Fig. 4, a fragmentary view as on line 4—4, Fig. 1, illustrating the improved trimming mechanism, and braking mechanism for operating the improved arbor, in inoperative position, the spinning tools being removed for purposes of clearness of illustration;

Fig. 5, a view similar to Fig. 4, the trimming tools having been operated, and the arbor brake being in operative position;

Fig. 6, a fragmentary enlarged view similar to Fig. 1, with portions in section illustrating more clearly the improved internal thread spinning arbor and other parts of the apparatus;

Fig. 7, perspective views of the improved thread roll and the improved internal thread spinning arbor, the thread roll being removed from the arbor, after a filler tube has been spun and trimmed; and

Fig. 8, a perspective view of an internally threaded filler tube made by the use of the improved apparatus and methods herein set forth, together with a perspective view of the filler tube cap therefor about to be screwed therein.

Similar numerals refer to similar parts throughout the drawings.

The improved apparatus for spinning internally threaded radiator filler tubes and the like, may include the improved metal spinning apparatus indicated generally at 1 and as illustrated and described in my copending

60

100

application for U. S. Letters Patent, Serial No. 134,432, and which improved apparatus includes a bed 2, having an improved spinning headstock 4 adjustably mounted in a well known manner at a desired longitudinal location thereon, and an improved tailstock 5 likewise adjustably mounted upon the bed in a well known manner at a desired longitudinal location adjacent the headstock.

10 Between the headstock and the tailstock a longitudinal feed carriage 6 is mounted in a well known manner for longitudinal movement between the headstock and the tailstock by rotation of the longitudinal feed carriage control wheel 7. A cross feed carriage 8 is mounted on the longitudinal feed carriage 6 for movement by operation of the cross feed carriage control crank 9 and a turret tool holder 10 may be mounted on the cross feed carriage 8.

15 For resisting both thrust and radial loads the improved headstock 4 is provided at its ends with tapered roller bearings 11 removably secured thereon as by caps 12 and co-25 operating studs 13 and nuts 14. A spindle drive shaft 15 is journaled in the bearings 11 for operative connection with a power shaft, not shown. At the spinning end 17 of the headstock the spindle shaft 15, which is preferably tubular, is provided with an inner 30 taper for receiving and fitting with the tapered end 19 of the improved thread spinning arbor 20.

25 The improved tailstock 5 is provided with a longitudinal aperture 37 axial with the arbor and spindle shaft, and in which aperture, screw 38 is slidably keyed as by a key 38' slideable in the keyway 38" of the screw, the screw extending towards the headstock beyond the 35 end 39 of the tailstock adjacent the headstock, and there being a thread apertured hand wheel 40 screwed upon the screw for abutment with the end 39 of the tailstock, the hub 41 of the handle being provided with an annular groove 42 in which a tailstock hand wheel finger 43 extends, the finger 43 being secured to the tailstock as by bolts 44, whereby the hand wheel may be rotated to move the screw towards or away from the arbor.

40 50 The foregoing construction and arrangement of the bed 2, the headstock 4, the tailstock 5, the longitudinal feed carriage 6, and the cross feed carriage 8, is all in accordance with the disclosure of my application for U. 55 S. patent as aforesaid, Serial No. 134,432.

The improved thread spinning arbor 20 having the tapered end 19 co-axial with and tightly fitting into the headstock spindle shaft 15, includes also co-axial with the headstock spindle shaft and with the tapered end 19, a stepped cylindric sleeve bearing 21, and an outwardly extending sleeve stop flange 22 is 60 preferably provided between the tapered end 19 and the stepped bearing 21.

The stop flange 22 is preferably cylindric

and externally threaded as at 22', and a thrust nut 22" is screwed thereon, forming an outward extension of the sleeve stop flange, and also providing means for removing the arbor from the spindle drive shaft, by unscrewing the nut to abut against the outer end of the spindle shaft.

65 A spinning form sleeve 23 is slidably mounted on the stepped sleeve bearing 21 and is provided with a pair of spaced outwardly extending sleeve flanges 24 and 24' forming an annular brake groove 25 for the sleeve. Bushings 26 and 26' are preferably provided between the sleeve and the stepped sleeve bearing.

70 At its outer end the stepped sleeve bearing 21 terminates in a thread roll bearing 27 preferably of a diameter smaller than the diameter of the outer smaller section of the stepped sleeve bearing, and the outer thread roll bearing is provided with a plurality of axially extending radial driving keys 28 thereon, for receiving and fitting into the plurality of longitudinally extending internal radial driving keyways 29 in the thread roll 30 having its outer cylindric surfaces provided with external threads 31 of the proper shape for forming the desired internal threads in the internally threaded filler tube.

75 80 For providing tapered necks for the filler tubes just below the internally threaded end, the sleeve 23 is provided with a tapered outer end 32, and for purposes hereinafter to be described in detail, a plurality of axially extending element grooves 33 are provided in the outer surface of the tapered end 32 of the sleeve.

85 90 Upon the cylindric outer surface 34 of the sleeve between its tapered outer end 32 and the flange 24', a stripping collar 35 is slidably mounted and provided with an external annular groove 36 which receives the upper bifurcated ends 45^a and 45^b of the vertically extending stripping fork 45 which is mounted at its lower end upon the end adjacent the arbor of a horizontally extending stripper rod 46; and the rod 46 is slidably mounted at its end adjacent the tailstock in hangers 47 depending from a collar 48 secured upon the shaft 38' of the screw 38 adjacent the inner end thereof, and preferably abutting the end 49 of the threads of the screw. A stop pin 46' extends from the rod 46 between the hangers 47.

95 100 105 For providing convenient means for inserting blank cups and the like upon the arbor, the unthreaded shaft 38' of the screw 38 extends toward the arbor beyond the collar 48, and forms a bearing for a cup inserting sleeve 50 slidably mounted thereon and provided with a handle 51 for moving the sleeve back and forth upon the shaft; and the shaft 38' terminates at its end adja- 110 115 120 125 130

cent the arbor, in the rotatable clamping head 52.

Upon a stub shaft 53 preferably mounted therein and extending from the rear stud 13 and the cap 12, the improved trimming mechanism and spindle braking mechanism indicated generally at 54 is operatively mounted, and includes a trimming tool supporting crank 55 pivotally journaled at the outer end of the stub shaft 53, and the crank carrying at its outer end a pair of spaced trimming tools, preferably rotary trimming tools 56 and 56' journaled upon a longitudinally extending trimming tool shaft 57 secured in the outer end of the crank 55, and the crank is further provided with a preferably upwardly extending handle 58 for pivoting the trimming tool up and down about the stub shaft as an axis.

20 Adjacent the crank 55 on the stub shaft, a sleeve flange stop arm 59 is secured, and the outer end of the stop arm extends at the tailstock side of the sleeve flange 24' preventing longitudinal movement of the sleeve 23 upon the sleeve bearing 21.

25 The braking mechanism for selectively preventing the normal rotation of the sleeve 23 with the sleeve bearing 21, includes the brake band 60 extending around the brake groove 25 of the sleeve 23 and secured at its outer ends upon the stub shaft 53 adjacent the stop 59, as by a screw 60'.

30 A brake rod 61 is mounted upon the crank 55 adjacent the trimming tools and extends longitudinally therefrom towards the headstock and over the brake band 60 whereby a downward pivoting of the crank 55 about the stub shaft 53 will eventually impinge the brake rod on top of the brake band and tighten the same about the brake groove to stop the rotation of the sleeve with the sleeve bearing for purposes hereinafter to be described in detail.

35 The turret tool holder 10 has mounted therein a laterally extending bracket 62 having a forked outer end which carries a preferably horizontal shaft 63 upon which are journaled preferably upon bearings of the ball or roller type, a pair of spaced rotary spinning rolls 64 and 65, and the neck spinning roll 64 nearest the headstock preferably has the grooved peripheral contour illustrated, and the thread spinning roll 65 nearest the tailstock preferably has a cylindric contour over the greater portion of its peripheral surface, and the cylindric contour being tapered off adjacent the headstock edge of the roll as illustrated.

40 The apparatus thus described in detail 60 may be used for spinning internally threaded radiator filler tubes and the like, such as the filler tube 66, illustrated in Fig. 8 together with the filler tube cap 67 therefor, by operating the apparatus as follows:

45 The spindle shaft and arbor are rotated at

a speed which may be 2250 R. P. M. A previously formed cup 62' is then inserted in the cup inserting sleeve 50 extended as illustrated in Fig. 2, and the thread roll 30 having been inserted upon the thread roll bearing 27 of the arbor 20 for being driven thereby through the keys 28 fitting into the keyways 29 of the thread roll, the clamping head 52 at the end of the shaft 38' of the screw 38 is advanced by means of the hand wheel 40 to clamp the disk end 62'' of the cup against the outer end of the thread roll whereby the thread roll and the cup extending over the same is caused to rotate with the arbor.

50 The sleeve 50 is then withdrawn as illustrated in Fig. 1, and by manipulation of the cross feed carriage control crank 9 and the longitudinal feed carriage control wheel 7 the cup is spun upon the longitudinally grooved and tapered sleeve 23 and the thread roll 30, by radial pressures applied upon the outer surface of the cup by the spaced spinning rolls 64 and 65 as they are longitudinally moved to and fro across the surface of the rotating cup.

55 In Fig. 1, the spaced rolls are illustrated in full lines in their extreme longitudinal position towards the tailstock and in dotted lines in their extreme longitudinal position towards the headstock.

60 In Fig. 6, the spaced spinning rolls are illustrated in full lines in their extreme longitudinal position towards the headstock and in dotted lines in their extreme longitudinal position towards the tailstock.

65 As best illustrated in Fig. 6 the thread spinning roll 65 serves to radially press and flow the material of the cup into the outer grooves of the thread roll 30, whereby internal threads of the proper shape are formed in the end portion 68 of the cup over the threads of the thread roll. The neck spinning roll 66 by its radial pressure and its longitudinal travel to and fro over the skirt of the cup serves to form a tapered neck 69 for the filler tube upon the tapered sleeve 23, and longitudinally extending internal ridges 70 are formed upon the inside of the tapered neck by the pressure of the spinning roll 64 against the material of the cup over the element grooves 33 in the tapered sleeve 23.

70 The peripheral surface of the thread roll 30 is preferably unthreaded and cylindric adjacent its outer end, whereby the disk end 62'' of the cup and the excess material at the end of the tapered neck may be simultaneously trimmed from the still rotating and now formed internally threaded filler tube by means of the properly longitudinally spaced and preferably rotary trimming tools 56 and 56' pivotally swung on the crank 55 into cutting contact with the rotating filler tube cap by means of the lever 58 as best illustrated in Figs. 4 and 5.

75 The operator does not of course trim the 130

formed filler tube as aforesaid until after withdrawing the spinning rolls from contact with the rotating filler tube, and at the same time the trimming operation is performed with one hand, the hand wheel 40 is turned to withdraw the clamping head 52 away from the arbor.

A further downward pivoting of the crank 55 about the stub shaft 53 eventually impinges the brake rod 61 upon the top of the brake band 60 and tightens the same about the brake groove 25, whereby rotation of the sleeve 23 and the filler tube now formed thereon and keyed thereto by the ridges 70 fitting in the grooves 33, is stopped, while the sleeve bearing 21 still rotates, driving the thread roll 30 with it through the keys 28 as aforesaid.

The stopping of the sleeve and the internally threaded filler tube upon the rotating sleeve bearing and thread roll causes the thread roll to screw out of the internally threaded filler tube and drop to be caught by the operator.

After the thread roll has been removed from the still rotating arbor, the crank 55 may be again elevated and the sleeve permitted to again rotate with the sleeve bearing, and the formed and trimmed filler tube 30 may then be stripped from the sleeve by further movement of the screw 38 away from the headstock by turning the hand wheel 40, whereby the stop pin 46' in the rod 46 is caught by the hanger 47 adjacent the headstock causing the stripper rod 46 to be drawn away from the headstock carrying with it the upper ends 45^a and 45^b of the stripping fork 45, and thereby stripping the filler tube from the sleeve and arbor and causing it to drop therefrom, as best illustrated in Fig. 3.

As best illustrated in Fig. 7, the keyways 29 in the thread roll 30 are preferably flared, and provided with one preferably longitudinal driving face 29' for abutment with the driving face of one of the keys 28, and an opposite diverging curved face 29'', whereby the keyway has a greater width at its headstock end than its tailstock end and thereby enabling the thread roll to be placed upon the thread roll bearing as it rotates with the spindle shaft, after which the aforesaid cycle of operations may be repeated and another internally threaded filler tube may be spun upon the continuously rotating arbor.

The cup 62'' may be previously formed in a drawing press, or may itself be spun by the use of the spinning apparatus set forth in my prior application, Serial No. 134,432.

When it is desired to spin external threads and the like, upon a tubular material by the method herein set forth, that is, by applying pressure on one side of material having another side in abutment with thread impressions and the like, it is obvious that the arbor herein set forth may be modified for pro-

viding a hollow central portion for receiving the material, and the thread roll may extend around the material, and the spinning roll may press from the inside of the material against the same as it externally abuts the internally threaded roll.

I claim:

1. The method of spinning threads and the like in tubular material and the like, which includes mounting the material upon an arbor having a circumferential surface fitting and contacting circumferentially with a circumferential surface of the material, the said arbor surface having grooves as thread grooves thereon, clamping the material to the arbor, rotating together the arbor and the material mounted thereon, and applying pressure upon a surface of the material opposite the surface contacting with the arbor.

2. The method of spinning ridges and grooves in tubular material and the like, which includes mounting the material upon an arbor having a circumferential surface fitting and contacting circumferentially with a circumferential surface of the material, the said arbor surface having ridges and grooves thereon, clamping the material to the arbor, rotating together the arbor and the material mounted thereon, and applying pressure upon a surface of the material opposite the surface contacting with the arbor.

3. The method of spinning threads and the like in a circumferential surface of tubular material and the like, which includes mounting the material upon an arbor having a circumferential surface fitting and contacting circumferentially with the circumferential surface of the material, the said arbor surface having grooves as thread grooves thereon, rotating together the arbor and material mounted thereon, and applying roller pressure upon a surface of the material opposite the surface contacting with the arbor for flowing the material into the arbor thread grooves and for cylindrically forming said roller pressed surface.

4. The method of spinning ridges and grooves in a circumferential surface of tubular material and the like, which includes mounting the material upon an arbor having a circumferential surface fitting and contacting circumferentially with the circumferential surface of the material, the said arbor surface having ridges and grooves thereon, rotating together the arbor and material mounted thereon, and applying roller pressure upon a surface of the material opposite the surface contacting with the arbor for flowing the material into the arbor grooves around the ridges and for cylindrically forming said roller pressed surface.

5. The method of spinning threads and the like in the inner surface of tubular material and the like, which includes mounting the material upon an arbor having an outer sur-

- face fitting and contacting circumferentially with the inner surface of the material, the said arbor surface having grooves as thread grooves thereon, clamping the material to the arbor, rotating together the arbor and the material mounted thereon, and applying pressure upon the outer surface of the material opposite the surface contacting with the arbor. 5
10. The method of spinning ridges and grooves in the inner surface of tubular material and the like, which includes mounting the material upon an arbor having an outer surface fitting and contacting circumferentially with the inner surface of the material, the said arbor surface having ridges and grooves thereon, clamping the material to the arbor, rotating together the arbor and the material mounted thereon, and applying pressure upon the outer surface of the material opposite the surface contacting with the arbor. 15
15. The method of spinning threads and the like in the inner surface of tubular material and the like, which includes mounting the material upon an arbor having an outer surface fitting and contacting circumferentially with the inner surface of the material, the said arbor surface having grooves as thread grooves thereon, rotating together the arbor and material mounted thereon, and applying roller pressure upon the outer surface of the material for flowing the material into the arbor thread grooves and for cylindrically forming the said material outer surface. 20
20. The method of spinning ridges and grooves in the inner surface of tubular material and the like, which includes mounting the material upon an arbor having an outer surface fitting and contacting circumferentially with the inner surface of the material, the said arbor surface having ridges and grooves thereon, rotating together the arbor and material mounted thereon, and applying roller pressure upon the outer surface of the material for flowing the material into the arbor grooves around the ridges and for cylindrically forming said material outer surface. 25
25. The method of simultaneously spinning threads and the like upon one portion of the inner surface of the tubular material and the like and spinning a neck adjacent the threaded portion of the tubular material, which includes mounting the material upon an arbor having a circumferential surface fitting and contacting circumferentially with a circumferential surface of the material, the said arbor surface having grooves as thread grooves thereon and a neck groove adjacent the thread grooves, rotating the arbor and the material mounted thereon, and simultaneously applying pressure upon the outer surface of the material over the thread grooves and over the neck groove. 30
30. Apparatus for simultaneously spinning threads and the like upon one portion of the inner surface of tubular material and the like and spinning a neck adjacent the threaded portion of the tubular material, which includes an arbor for mounting the material to be spun, the arbor having grooves as thread grooves thereon and a neck groove adjacent the thread grooves, means for rotating the arbor and the material mounted thereon, means for clamping the material to the arbor and means for simultaneously applying pressure upon the outer surface of the material over the thread grooves and over the neck groove. 35
35. Apparatus for simultaneously spinning ridges and grooves upon a portion of the inner surface of tubular material and the like and spinning a neck adjacent the threaded portion of the tubular material, which includes an arbor for mounting the material to be spun, the arbor having ridges and grooves thereon and a neck groove adjacent the ridges and grooves, means for rotating the arbor and the material mounted thereon, means for clamping the material to the arbor and means for simultaneously applying pressure upon the outer surface of the material over the ridges and grooves and over the neck groove. 40
40. Apparatus for spinning ridges in tubular material and the like, which includes an arbor having grooves therein for fitting within and mounting material to be spun, means for clamping the material to the arbor, means for rotating the arbor and the material mounted thereon, and means for applying pressure upon a surface of the material opposite the arbor grooves. 45
45. Apparatus for spinning ridges in the inner surface of tubular material and the like, which includes an arbor having outer grooves thereon for fitting within and mounting material to be spun, means for clamping the material to the arbor, means for rotating the arbor and the material mounted thereon, and means for applying pressure upon the outer surface of the material opposite the arbor grooves. 50
50. The method of simultaneously spinning ridges and grooves in the inner surface of tubular material and the like, which includes mounting the material upon an arbor having a circumferential surface fitting and contacting circumferentially with a circumferential surface of the material, the said arbor surface having grooves as thread grooves thereon and a neck groove adjacent the thread grooves, rotating the arbor and the material mounted thereon, and simultaneously applying pressure upon the outer surface of the material over the thread grooves and over the neck groove. 55
55. Spinning apparatus including a ro-

tatable arbor sleeve bearing, an arbor sleeve slidably mounted upon the bearing and normally rotatable therewith, and means for selectively stopping rotation of the sleeve with the rotating bearing.

5 16. Spinning apparatus including a rotatable arbor sleeve bearing, an arbor sleeve slidably mounted upon the bearing and normally rotatable therewith, and means for selectively stopping rotation of the sleeve with the rotating bearing, and a removable thread roll mounted upon the sleeve bearing.

10 17. Apparatus for spinning threads and the like in tubular material and the like, which includes an arbor, means for clamping material to the arbor, and associated means for forming threads and the like in tubular material mounted on the arbor, and means for unscrewing the threaded material from the arbor.

15 18. Apparatus for spinning threads and the like in tubular material and the like, which includes an arbor, a removable thread roll thereon, means for clamping material on the arbor and the thread roll, means for forming threads and the like in the material mounted on the arbor and thread roll, means for simultaneously trimming the threaded material and unscrewing the thread roll therefrom, and means for stripping the threaded material from the arbor.

20 19. Apparatus for spinning threads and the like in tubular material and the like, which includes an arbor, a removable thread roll thereon, means for clamping material on the arbor and the thread roll, means for forming threads and the like in the material mounted on the arbor and thread roll, and means for simultaneously trimming the threaded material and unscrewing the thread roll therefrom.

25 20. Spinning apparatus including a rotatable arbor, means for mounting tubular material and the like on the arbor including a shaft separate from the arbor and aligned therewith, and a slideable sleeve on the shaft for selectively extending over the arbor.

In testimony that I claim the above, I have hereunto subscribed my name.

REYNOLD G. NELSON.
